UNITED STATES PATENT OFFICE.

CHARLES POKORA, OF MILWAUKEE, WISCONSIN.

LEAF HOLDER.

Application filed January 19, 1928. Serial No. 247,904.

This invention relates to improvements in leaf holders.

It is one of the objects of this invention to provide a leaf holder for use upon books, notebooks, and the like, which will maintain the pages in position while the book is being used.

It is a further object of this invention to provide a leaf holder which will serve as a book-mark, automatically keeping the proper place as the pages are turned.

It is a further object of this invention to provide a leaf holder which is constructed of a single length of wire without the use of any plate member or other means commonly employed for strengthening the clip.

It is a further object of this invention to provide a leaf holder which is very simple in construction, is inexpensive, and is well adapted for the purpose described.

With the above and other objects in view, the invention consists of the improved leaf holder and all its parts and combinations as set forth in the claims and all equivalents.

In the accompanying drawing, in which the same reference characters designate the same parts in all of the views:

Fig. 1 is a plan view of an open book with both left and right hand leaf holders in attachment therewith, part of the book being broken away;

Fig. 2 is a sectional view on the line 2—2 of Fig. 1, the book being closed, and only one leaf holder being shown; and

Fig. 3 is a front view of a closed book with one of the leaf holders in attachment therewith, part of the book being broken away.

Fig. 4 is an elevation of part of the device on a larger scale with parts in section to disclose the interconnection of the parts.

Referring to the drawing, the numeral 5 designates a book to which is attached the improved leaf holder. The latter comprises a single length of wire bent to form a finger 6, a loop 7, a thumb projection 8, an arm 9, a coil spring 10, a brace 11, and a clip member 12. The thumb projection 8 is but a very slight bend at the end of the loop 7 to enable the finger 6 to be raised up when it is desired to insert a leaf.

The brace 11 is a very important part of the device as it receives all of the strain caused by the tightening of the spring 10 when the finger 6 is raised. As the brace bears against the cover of the book, the finger can be raised

without affecting the clip portion 12. Without this brace the strain would be imparted to

the clip and it would be raised up and caused to separate from the cover upon every manipulation of the finger 6. In other types of leaf holders, plates have been used either as the entire clip member or to strengthen a wire clip to hold it in proper engagement. In this invention, the use of the brace to strengthen the clip eliminates the necessity of having a plate or other separate part, and thus simplifies the leaf holder by permitting it to be constructed entirely of a single length of wire.

A further novel feature of this invention resides in the fact that the coil spring fits outside of the leaves on the edges thereof, as shown in Fig. 2, thus eliminating the projection caused in many devices when the spring is positioned underneath the leaves.

In using the device two leaf holders may be employed as shown in Fig. 1, one constructed for the left hand cover and one for the right, or a single holder may be used. The device for the right hand cover acts as an automatic book-mark, for as the leaves are withdrawn and turned, it automatically engages the next leaf. If the book is closed, it will mark the place where the user left off. The holders for both covers are designed to hold the pages in place to prevent their turning of their own accord or because of a breeze. When a device for the left hand cover is employed, as a page is turned it is merely necessary to engage the projection 8 with the thumb or finger, and raise the finger 6 to insert the leaf, or to slip the leaf under the finger without raising the latter.

From the foregoing description it may be seen that the improved leaf holder is simple in construction, is inexpensive to manufacture, and is well adapted for the purpose described.

What I claim is:

1. A leaf holder comprising a clip portion, a spring in connection with said clip portion, a brace member in connection with said spring and extending within the clip portion, and an arm joining said spring and extending in an opposite direction from the brace member.

2. A leaf holder comprising a clip portion, a spring in connection with said clip portion, a loop-shaped brace member in connection with said spring and extending within the clip portion, and an arm joining said spring and extending in an opposite direction from the brace member.

3. A leaf holder comprising a wire clip portion having two U-shaped sides, a spring in connection with an upper end portion of

said clip, a brace in connection with said spring and extending between the two sides of the clip, and an arm joining said spring and extending in an opposite direction from the brace member.

4. A leaf holder comprising a wire clip portion having two U-shaped sides, a small coil spring in connection with an upper end of said clip, a loop-shaped brace member in connection with said spring and extending between the two sides of the clip, an arm joining said spring and extending in an opposite direction from the brace member, said arm having an upwardly bent end portion, and a finger extending downwardly from said arm.

5. A leaf holder consisting of a single length of wire bent to form a clip portion, a spring at an upper end of said clip portion, a loop extending from the spring within the clip portion, and an arm extending from the spring in an opposite direction from the loop.

6. A leaf holder consisting of a single length of wire bent to form a clip portion having two U-shaped sides, a coil spring at

an upper end of said clip portion; a loop-shaped brace extending from the spring between the sides of the clip, an arm extending from the spring in an opposite direction from the brace, a slight upward projection at the end of said arm, and a finger extending downwardly from the arm.

7. A leaf holder consisting of a single length of wire bent to form a clip portion having two U-shaped sides, a small coil spring at an upper end of said clip, the free end of the clip portion being within the coil spring, a loop-shaped brace member extending from the spring between the sides of the clip, an arm extending from the spring in a direction opposite from the brace, a slight upward projection at the end of said arm, and a finger extending downwardly from the arm.

8. A leaf holder consisting of a single length of wire bent to form a clip portion, a spring in connection with said clip portion, a base member extending from the spring and an arm extending from the spring.

In testimony whereof, I affix my signature.

CHARLES POKORA.

CERTIFICATE OF CORRECTION.

Patent No. 1,710,949.

Granted April 30, 1929, to

CHARLES POKORA.

It is hereby certified that error appears in the printed specification of the above numbered patent requiring correction as follows: Page 2, line 47, claim 8, for the word "base" read "brace"; and that the said Letters Patent should be read with this correction therein that the same may conform to the record of the case in the Patent Office.

Signed and sealed this 4th day of June, A. D. 1929.

(Seal)

M. J. Moore,
Acting Commissioner of Patents.
